UNITED STATES PATENT OFFICE.

ARTHUR E. RIDEOUT, OF CHICAGO, ILLINOIS, ASSIGNOR TO NATIONAL BINDING MACHINE COMPANY, OF NEW YORK, N. Y., A CORPORATION OF NEW YORK.

STRIP-SERVING DEVICE.

1,384,090.

Specification of Letters Patent. Patented July 12, 1921.

Application filed April 13, 1914, Serial No. 832,705. Renewed October 30, 1920. Serial No. 420,853.

To all whom it may concern:

Be it known that I, ARTHUR E. RIDEOUT, a citizen of the United States, and a resident of Chicago, in Cook county, State of Illinois, have invented an Improvement in Strip-Serving Devices, of which the following description, in connection with the accompanying drawings, is a specification, like letters on the drawings representing like parts.

The present invention relates to strip serving devices designed to moisten, cut and deliver strips of adhesive tape for use in connection with sealing packages and the like.

15 The object of the invention is to provide an apparatus wherein the tape may be held against or away from the moistener at the will of the operator and independently of the draft on the tape.

20 One embodiment of the improvements constituting my invention is illustrated in the accompanying drawings in which,

Figure 1 is a side elevation and

25 Fig. 2 is a view partly in section on line 2-2 of Fig. 1.

It will be understood that the present invention has to do with devices for delivering strips of adhesive tape, comprising a support for a supply of tape, moistening means 30 either to moisten tape already gummed or to apply adhesive paste to unguammed tape, means for guiding the free end of the tape and suitable severing means for cutting off strips of desired length. Referring to Fig.

35 1 of the drawings, a tape support 1 is mounted upon a suitable base 2. Adjacent thereto is located a receptacle 3 for holding water or paste and in which a moistener 4 rotates when a strip of tape 18 is drawn across its

40 exposed surface. When the tape has been properly moistened, the strip is severed by means comprising a suitably mounted fixed blade 5 and a movable blade 6 positioned to coöperate with the fixed blade. It is not es-

45 sential that there be two blades because the strip may be severed as well merely by deflecting it against either the fixed blade or the movable blade in case only one is used.

In order that the free end of the tape may 50 be held away from the moistener when the device is not in use, I have provided a movable tape guiding member comprising a suitable frame 12, guide rollers 7 and 8 to engage the dry strip, and guide rollers 9 and 55 10 to engage the strip after it passes the

moistening roller. Between these two sets of rollers, I also provide a presser roller 11 adapted to press the tape positively against the moistening roller 4 when the entire guiding member is deflected downwardly 60 toward the moistening roller. In order that the tape through normally out of contact with the moistening roller, may be readily pressed downwardly against the moistener at the will of the operator I mount the frame 12 65 of the guiding member upon suitable spring cushioned rods 13 which retain the guiding member in normal position. When it is desired to moisten a strip of tape, the operator may depress the guiding member 70 until the presser roller presses the tape against the moistening roller, simply by pressing with his foot upon a treadle 14 which in turn connects with the spring supported rods by means of a connecting rod 15 and a 75 plate 16 to which the said rod is pivoted and which also serves as a base plate to connect the several supporting rods. When the guiding member is thus depressed, the operator may take hold of the free end of the 80 tape which normally rests behind the severing means 5, and draw out a strip to the desired length. In so doing, he may subject it to any desired pressure in its passage across the moistening roller, thus insuring 85 the proper degree of moistening to secure thorough impregnation of the gum on the tape, in case it has previously been gummed. When a sufficient length of tape has been drawn out, it may be detached by releasing 90 pressure upon the treadle 14, causing the guiding member to return to its normal position and at the same time bringing the movable knife 6 into operative relation with the fixed knife to sever the strip which intervenes. It will be understood that the 95 presser roller 11 and the guiding rollers 9 and 10 between which the tape passes after it has been moistened are formed with peripheral projections 17 in the latter case so 100 that the adhesive tape will not have a substantial surface upon which to stick when a machine is not in operation and in the former, so that moisture may not reach the unguammed side of the tape. It is obvious 105 that fixed guide bars might be substituted for the guide rollers 7 and 8 and that various other parts may be replaced by equivalents without departing from the spirit of the invention which lies in providing in 110

a strip serving device, means for controlling the position of the tape relative to the moistener, the said means being operative at will by the user of the machine and independent 5 of draft on the tape.

I claim as my invention—

1. A device for serving adhesive strips of tape comprising in combination, a support for a supply of tape, means for moistening the tape to render it adhesive, a yielding support having guide rollers for the free end of the tape, and severing means, comprising a fixed blade and a blade mounted on the yielding support and adapted to coact with 10 the fixed blade to sever a strip of tape at the will of the operator.
2. A device for serving adhesive strips of tape comprising in combination a support for a supply of tape, means for moistening the tape to render it adhesive, a frame having strip guiding means and a strip presser interposed between said guiding means, and means for moving said guiding means and said presser toward the moistening means.
3. A device for serving adhesive strips of tape comprising in combination a support for a supply of tape, means for moisten- 20 25

ing the tape to render it adhesive, a frame having strip guiding rollers and a strip-pressing roller interposed between said guid- 30 ing rollers, and means for moving said guid- ing rollers and the pressing roller simultane- 35 40 45 anously toward the moistening means.

4. A device for serving adhesive strips of tape comprising, in combination, a support for a supply of tape, means for moistening the tape to render it adhesive, a yielding support having guide rollers for the free end of the tape, a presser mounted on the yielding support and adapted when moved in one direction to press the tape into moisture-receiving position, and severing means, comprising a fixed blade and a blade mounted on the yielding support and adapted when moved in one direction to coact with the fixed blade to sever a strip of tape.

In testimony whereof, I have signed my name to this specification, in the presence of two subscribing witnesses.

ARTHUR E. RIDEOUT.
